DESIGN FOR A LADY'S SKIRT.

SPECIFICATION forming part of Design No. 14,431, dated November 20, 1883.
Application filed September 26, 1883. Term of patent 3½ years.

CATHERINE O'HARA.

Witnesses:

ALFRED FRANCIS,
MARCELLUS CARLETON SHATTUCK.

UNITED STATES PATENT OFFICE.

CATHERINE O'HARA, OF NEW YORK, N. Y., ASSIGNOR TO THE BUTTERICK PUBLISHING CO., (LIMITED,) OF SAME PLACE.

DESIGN FOR A LADY'S SKIRT.

SPECIFICATION forming part of Design No. 14,431, dated November 20, 1883.

Application filed September 26, 1883. Term of patent 3½ years.

To all whom it may concern:

Be it known that I, CATHERINE O'HARA, of the city, county, and State of New York, have invented and produced a new and original Design for a Pattern of a Lady's Overskirt, (numbered 8,906;) and I do hereby declare that the engraved prints accompanying this specification convey to any one accustomed to using paper patterns a clear understanding of how a garment made up by the pattern will appear.

The design combines a deep front drapery that shapes a point at the right side of the

front, and a deep back drapery that is draped by plaits at the belt, rounds away from the 15 seam at the left side, and falls straight at the right side.

What I claim as my invention, and desire to secure by Letters Patent, is—

The design for a lady's overskirt, as shown in 20 the engraved prints accompanying this specification.

CATHERINE O'HARA.
